UNITED STATES PATENT OFFICE.

CARL J. HAZELTON, OF WORCESTER, MASSACHUSETTS, ASSIGNOR TO AMERICAN NARROW FABRIC COMPANY, OF WORCESTER, MASSACHUSETTS, A CORPORATION OF MASSACHUSETTS.

HOSE SUPPORTER.

Application filed March 26, 1921, Serial No. 455,764. Renewed December 15, 1922.

To all whom it may concern:

Be it known that I, CARL J. HAZELTON, a citizen of the United States, residing at Worcester, in the county of Worcester and

5 State of Massachusetts, have invented a new and useful Hose Supporter, of which the following is a specification.

This invention relates to a hose supporter of the type in which a metallic loop is employed to grip the fabric between its two arms and a button carried by a tab usually depending from the upper part of the loop. As heretofore put on the market, these clasps have had a serious fault due 15 to the fact that when the stocking is gripped and put under strain, that strain comes along a central vertical line and therefore is sustained only by a button or stud which has a rubber covered top or head with only 20 one stud centrally located to stand the strain.

This invention is designed to overcome this defect. More specifically stated, this invention involves the provision of a rubber covered button of such a nature that 25 when the strain is put on the fabric it will be sustained by two separate studs in a horizontal plane; to provide a construction in which the rubber covering of the button is held firmly in position by a solid body 30 of rubber extending under the heads of the studs, and to provide effective and inexpensive means for preventing the button from turning on its support so that the above mentioned objects will be maintained after 35 wear.

The invention also involves other features of construction which tend to assist in accomplishing the above mentioned objects as will appear.

40 Reference is to be had to the accompanying drawings, in which—

Fig. 1 is a front elevation of a stocking supporter clasp constructed in accordance with this invention and showing it as it holds the stocking in position under strain;

45 Fig. 2 is a similar view showing the parts with the stocking fabric removed;

Fig. 3 is a side elevation with the parts in the same position;

50 Fig. 4 is a central vertical sectional view taken along the line 4—4 of Fig. 1;

Fig. 5 is a front elevation showing the button and its supporting base plate removed from the rest of the clasp;

Fig. 6 is a central sectional view of the 55 same;

Fig. 7 is a view similar to Fig. 5 showing a modification;

Fig. 8 is a central sectional view of the 60 same, and

Fig. 9 is a similar view of another modification.

The invention is shown as applied to a construction involving an upper supporting loop 10 of well-known construction for receiving the elastic strap of the supporter. It is pivotally connected with a lower metallic loop 11. This loop 11 is provided with almost parallel but slightly converging side arms 12. At a point just below 70 where they engage the shank of the button they diverge from each other to form end portions 13. These are connected across the end of the loop by a straight transverse bar 14. These parts, of course, are all formed 75 of a single piece of wire or metal stamping and preferably are integral with each other. They form a button receiving loop at the bottom of the main loop 11.

Also supported by the loop 10 and hanging down behind the loop 11 is a piece 15 of textile material, usually in the form of non-elastic tape. This is provided on the bottom with a metal collet-supporting base plate 16 supported in vertical position in 85 the usual or any desired way. This plate has the usual transverse perforations for receiving the tape 15 and it is also provided with two parallel integral projections 17 extending in front of its normal plane. 90

Between the projections but spaced from them are two rivets 18 located at a distance apart but at the same elevation. These are shown as provided with rectangular heads 19 arranged symmetrically with respect to 95 their shanks. These heads are shown of such length that they butt against each other at the center. These rivets are in the form of shanks, together constituting the support for the button or collet. The collet or covering 20 is provided with an elongated head formed with a central depression 21 shaped to receive the two heads 19, which are below the level of the front of the button. Above and below this depression are walls 22 105 formed from the soft rubber and integral with it. From the outside of each of these walls the button descends in two parallel

planes perpendicular to the plate 16. It is to be noted also that the head of the collet as well as the heads of the rivets 18 project out at 24 over the shank of the stud or collet 5 to overlie the side arms 12 which are received back of it beneath these projections, as indicated in Fig. 6. By having the heads of the rivets 18 extend over or beyond the shank of the stud, the head of the stud or collet is 10 reinforced, a solid backing being provided for that portion of the collet which lies immediately above the side arms of the holding loop when the loop is in holding position relatively to the collet. By making the bar 15 14 longer than the width of the loop 11 all this action is rendered possible and side spaces are provided to receive the longitudinal wrinkle produced in the fabric.

The security with which the button or 20 collet is held as described fully above is an important feature. This is assisted by the projections 17 which are parallel and engage the upper and lower flat walls of the button to keep it from turning.

25 In the form shown in Figs. 7 and 8 I have introduced a modification which consists in making these two rivets integral with each other by connecting the shanks 30 across the top at 31. In both cases a block of rubber 30 35 is held under the heads of the rivets, or under this cross bar 31, to prevent the withdrawal of the collet from its supporting parts. This piece of rubber 25 of course is integral with the walls of the collet and therefore constitutes a positive means for holding the parts in place.

40 In the form shown in Fig. 9 two studs 33 are shown with their heads resting on a metal plate 39, which holds the rubber and positively spaces the studs. No claim is made herein to the construction of the 45 supporter in which the head has a groove on its front surface with the lower thin readily yieldable wall of rubber projecting beyond the edge of the groove along the lower side thereof to yield toward the groove under excessive strain as that is claimed in my Patent No. 1,432,693.

50 Although I have illustrated and described only three forms of the invention I am aware of the fact that other modifications can be made therein by any person skilled in the art without departing from the scope of the invention as expressed in the claims. 55 Therefore, I do not wish to be limited to all the details of construction herein shown and described but what I do claim is:—

1. As an article of manufacture, a hose 60 supporter comprising a metal plate, a pair of rivets passing through the plate, said rivets having flat heads thereof projecting toward each other into contact at their edges, and a rubber covering mounted on said rivets and having an elongated groove at its 65 front face in which said heads are located,

said rubber covering having an integral interior portion extending under said heads and between the shanks of the rivets for positively preventing the disengagement of the covering from the metal plate. 70

2. As an article of manufacture, a hose supporter button having a base-plate, a plurality of parallel holding members connected thereto and having portions extending toward each other at their extreme opposite ends at a distance from the plate, and a single integral rubber covering mounted on and surrounding said members and having an elongated groove in its front face in 75 which the end portions of said parallel holding members are located, said rubber covering having an integral interior portion extending between said parallel holding members all the way from the plate to said end portions for positively preventing the disengagement of the covering from the plate, 80

3. As an article of manufacture, a hose supporter comprising a metal plate, a pair of rivets passing through the plate, said rivets having heads thereon, the edges of 85 which substantially come into contact, and a rubber covering mounted on said rivets and having a depression in which said heads are located, said rubber covering having an integral interior portion extending under said 90 heads and between the shanks of the rivets for positively preventing the disengagement of the covering from the metal plate, 95

4. As an article of manufacture, a hose supporter comprising a metal plate, a pair 100 of shanks extending from the plate, said shanks having rectangular heads, the ends of which substantially come into contact so that they form a practically continuous metal plate for holding the button, and a 105 rubber button mounted on said shanks and having a depression in which said heads are located.

5. As an article of manufacture, a rubber collet for a hose supporter having a longitudinal groove on its front face and a plurality of parallel passages therethrough 110 from front to rear terminating in said groove through which it can be fastened to a base plate. 115

6. In a hose supporter the combination of a holding loop, a collet cooperating therewith, a base plate, and a pair of headed rivets for securing the collet to said base plate, the heads of said rivets overlying the side arms of said loop when the loop is in operative position relatively to said collet. 120

7. In a hose supporter the combination of a holding loop, a button or collet cooperating therewith, a base plate, and a pair of 125 headed rivets for securing said button or collet to said base plate the heads of said rivets contacting with each other and overlying the side arms of said loop.

8. In a hose supporter the combination 130

- of a holding loop, a button or collet cooperating therewith, a base plate, and a pair of rivets having rectangular heads for securing said button or collet to said base plate, the rectangular heads of said rivets overlying the side arms of said loop when the loop is in operative position relatively to said button or collet.
9. In a hose supporter the combination of a holding loop, a button or collet cooperating therewith, a base plate, and a pair of rivets for securing said button or collet to said base plate, said rivets being provided with rectangular heads in contact with each other said heads overhanging the side arms of said loop when the loop is in operative position relatively to said button or collet.
10. In a hose supporter the combination of a holding loop, a button or collet cooperating therewith, a base plate, and a pair of rivets for securing said button or collet to said base plate, said rivets having rectangular heads in contact with each other and overlying the side arms of said loop when the loop is in operative position relatively to said button or collet, said rectangular heads lying in a substantially rectangular groove or depression in the head of said collet.
11. In a hose supporter the combination of a collet, a base plate, and a pair of rivets passing entirely through said collet for securing the collet to said base plate, said rivets having non-circular heads in contact with each other and lying in a correspondingly shaped groove or depression in the head of the collet said rivet heads and groove cooperating to prevent turning of the collet on said rivets.
12. As an article of manufacture a hose supporter comprising in combination a button having an elongated head and a shank the head of said button having a groove on its front surface running longitudinally thereof, a base plate and means having a head lying in said groove and co-operating with said groove for securing said button to the base plate.
13. As an article of manufacture a hose supporter comprising in combination a button having an elongated head and a shank, the head of said button having a groove on its front surface running longitudinally thereof, a base plate and securing means comprising two rivets the heads of which are located in said groove.
14. In a hose supporter the combination of a holding loop, a collet co-operating therewith and provided with an elongated head extending transversely of said loop, a support for the collet, and means for securing said collet to its support, said securing means being provided with an elongated head extending lengthwise of said collet and overlying the side arms of said loop when the loop is in operative position relatively to said collet.
15. In a hose supporter the combination of a holding loop, a collet co-operating therewith and provided with a head, a base plate, and means for securing said collet to its base plate, said securing means being provided with a head overlying the side arms of said loop and lying in and co-operating with a correspondingly-shaped depression or groove in the face or surface of the head of said collet.

In testimony whereof I have hereunto affixed my signature.

CARL J. HAZELTON.
